UNITED STATES PATENT OFFICE.

HENRY HIGGIN, OF NEWPORT, KENTUCKY, ASSIGNOR OF ONE-HALF TO THE HIGGIN MANUFACTURING COMPANY, OF NEWPORT, KENTUCKY, A CORPORATION OF WEST VIRGINIA.

WINDOW-SCREEN.

1,092,442.

Specification of Letters Patent.

Patented Apr. 7, 1914.

Application filed April 7, 1913. Serial No. 759,322.

To all whom it may concern:

Be it known that I, HENRY HIGGIN, a citizen of the United States, and a resident of the city of Newport, in the county of Campbell and State of Kentucky, have invented certain new and useful Improvements in Window-Screens, of which the following is a full, clear, and exact description, reference being had to the accompanying drawings, forming part of this specification.

The object of my invention is to provide a construction of metal frame for window screens which shall be rigid, durable, readily and easily put together, and in which the means provided for locking and holding the wire screening shall be so arranged that the wire screen can be easily released and the screen rewired in the field, should the original screening become damaged or destroyed.

A further object relates to the arrangement of a more effective construction for holding the screen in the window guides, by which the narrow flat springs heretofore employed are dispensed with.

A further object is to provide for the ready and easy attachment of the finger lifts to the molding without interfering with the removal and replacement of the screening.

The several features of my invention and the various advantages resulting from their use conjointly or otherwise will be apparent from the following description and claims.

In the drawings, Figure 1 is a plan view of one corner of my improved screen. Fig. 2 is a transverse section, in perspective, of a portion of the top and bottom molding showing the method of locking the wire screening. Fig. 3 is a perspective view of one end of the molding for the sides of the frame, with the screening removed. Fig. 4 is a longitudinal section of one corner of the frame showing the method of securing the springs. Fig. 5 is a front elevation of the same. Fig. 6 is a front elevation of a portion of the frame illustrating the finger lift. Fig. 7 is a transverse section of the same. Fig. 8 is a section of the frame molding and guide rail for one side of the window frame, and Fig. 9 is a section of the opposite guide rail,—these two views illus-

trating the differences in height of the two rails. Fig. 10 is a perspective view of the corner pieces.

My improved framework or molding for the window screen is formed in suitable dies, preferably from an integral strip of sheet metal for each of the four sides of the frame. The strip is for one longitudinal edge curved and bent over on itself to form a substantial semi-cylindrical portion made up of the semi-cylindrical walls 1 and 2. The strip of sheet metal is also bent to form the flat front face 3 of the molding, and for the two sides of the molding frame the metal sheet is bent inwardly to form the bottom 4 and the two side walls 5, 6, of a groove which is adapted to ride on the vertical guide rail in the window frame. The metal strip is then bent to form the opposite side of the molding frame 7, substantially parallel with the wall 3, and the strip is then bent inwardly to form an oblique portion 8, and the edge turned over to form a flange and preferably curved into a slight arc 9. This construction of the molding with the grooves is provided for the sides of the screen frame, and for the bottom and top the construction is the same, except that a flat bottom 10 is formed instead of a groove. With this construction, the curved portion 1, 2, especially with the lower edge of the strip 12 locked around the base of the curve, forms a rigid and substantial seat for the rod 13. The oblique member 8 of the molding with the side portion 9 forms a resilient member and a holding edge for the rod.

The wire screening 35 having been cut of the desired size, is laid within the segmental seat formed by the walls 1 and 2, and the rods 13 are then pushed into place so as to bear between the seat 9 and the opposite seat. The oblique wall 8 bends slightly to permit the passage of the rod and then springs back in front of the rod so as to hold it securely. It is not necessary to form a connected framework of the rods; but four locking rods are provided, one for each side of the screen, and these rods are pushed into place one at a time. This forms a very effective construction for holding the wire, while at the same time whenever it is desired to replace the wire screening, the molding may

be sprung so as to release the rods, new screening can be inserted and the rods replaced without difficulty.

The sides and bottom and top pieces making up the window screen frame are beveled at the corners to fit together, as shown at 14, and in order to lock and hold together the corners and at the same time provide a spring construction for holding the window screen on the guide rails in the window and to permit the screen to be removed and replaced, I provide as follows: A sheet metal box is formed of the sides 15, 15, with right angled extensions 17, 18, and with a connecting base 19, as shown in Fig. 10. The end wall 20 is formed preferably by turning over the ends of the walls 15, 16, with a circular opening 21 in the end wall, in which is mounted the rod 22, preferably provided with a head 23. A coiled spring 24 (Fig. 4) is mounted between the end wall 20 and the head 23, the tendency of which is to project outwardly the rod or bolt 22. The boxing is pushed into the top and bottom portions of the molding. The sides 15, 16 are preferably made to conform to the heights of the walls 3 and 7, and the width of the box is such as to fit snugly in the molding. The right angled plates 17, 18 are then passed into the grooves formed by the walls 3 and 5, and 6 and 7 of the grooved members of the molding. These parts of the boxing fit snugly into the respective members of the molding frame, and the members of the frame are held rigidly and securely at the corners by sweating or brazing after the parts have been inserted. A rectangular loop of sheet metal, with a long arm 25 and a short arm 26 and a connecting base 27, is slipped over the head of the bolt 22, with the short arm formed with a slight hook 28 to engage under the edge of the base 4 of the groove, and with the longer member 25 pushed in along the bottom 19 of the boxing. In this way, a smooth bearing surface 27 is provided for engagement with the guide rails for the screen. These guide rails are preferably hollow rails 29 and 30, vertically secured by screws 31, 31, to the pulley stile, and one of the rails is approximately twice the height of the other.

The spring bolts, it will be understood, are only provided for one side of the frame at top and bottom. For the other corners, the same angle pieces are employed for securing and bracing the corners, but the bolts and springs are omitted, because it is only necessary to have the spring construction on one side. The springs are employed for the side, arranged to engage the rail 29, while for the rail 30 no spring devices are employed.

In order to locate the screen in position in the window, the screen is inserted by compressing the springs until the opposite side

of the screen will pass the shallower rail 30, and then the springs are allowed to shift the screen so that both rails are engaged. In order to permit this compression of the springs, the bottom plate 19 is cut away at 32. 70

In the ordinary constructions a flat spring is used at the base of the groove, and this flat spring must either be sufficiently powerful so that it is difficult to compress the same, or considerable space must be given up to the springs. With my improved construction as above outlined, the springs themselves are located in the hollow portion of the molding of the top and bottom 80 portions so that ample space is provided for, and coiled springs can be used, which are much more uniform and effective in their operation than flat springs.

My construction of molding also lends 85 itself to ready and easy attachment of the lifts for raising the screen. A plate 36 is provided, which is curved to fit around the semi-circular wall 2. This plate is formed with an upwardly projecting loop 37 which is raised at its middle portion at 38, and the opposite edge of the plate is folded back under the folded-over edge of the molding walls 1, 2, at 39. The edge of the walls 1, 2, is raised slightly where clasped by the lift 90 holding plate, so that a smooth seat is left for the locking rods 13, without any interference from the attachment. The finger loop 40 is then inserted, with its inner ends engaged by the loop 37, and with the inner 95 ends bent upwardly slightly, as indicated at 41 in Fig. 6, so that these ends will come within the raised portion 38 of the holding plate. With this construction, the finger loops 40 will be held in upright position out 100 of the way in close contact with the wire mesh. They can easily be turned outwardly for the insertion of the fingers for raising the screen, and as soon as the finger loops are released, they are returned to their normal upright position, by reason of the fact that in turning the loops on the pivotal portion of the plate, the ends of the finger loops are brought in contact with the contracted 105 narrower portion of the plate walls, so that 110 there is sufficient resiliency to bring the finger loops back to their upright position as soon as released.

In order to hold the plates 36 in position, it will be found preferable to solder same to 115 the wall 2, although they may be secured in any other convenient way. As many of these lifts are provided as desired, preferably two for the bottom of the frame and one for the side of the frame opposite the springs. 120

Having thus described my invention, what I claim as new and desire to secure by Letters Patent, is:—

1. In a window screen, in combination with the wire screening, a frame therefor 130

formed from an integral strip of sheet metal, bent into hollow shape with its longitudinal side edges projecting toward the screening, one edge formed into a seat segmental in cross section, and the other edge bent obliquely toward the opposing seat to form a resilient locking member, with a rod between which and the segmental seat the wire screening is engaged, and the rod locked in position by the resilient member of the molding.

2. In a window screen, in combination with the wire screening, a frame therefor formed from an integral strip of sheet metal, bent into hollow shape, with one side portion formed into a seat segmental in cross section, and the other side portion bent obliquely toward the opposing seat to form a resilient locking member, and provided with an inwardly extending flange, with a rod between which flange and the segmental seat the wire screening is engaged, and the rod locked in position by the flange along the resilient member of the frame.

3. In a window screen, in combination with the wire screening, a frame therefor formed from an integral strip of sheet metal, bent into hollow shape with its longitudinal side edges projecting toward the screening, one edge formed into a seat segmental in cross section, and the other edge bent obliquely toward the opposing seat to form a resilient locking member, and having the molding for the vertical sides of the frame bent inwardly to form a groove, with a rod between which and the segmental seat the wire screening is engaged, with the rod locked in position by the resilient member of the molding, and a box having a telescopic engagement with the top and bottom portions of the frame, with plates extending at right angles from the box, having

telescopic engagement with the groove walls of the side portions of the frame to lock the frame at the corners.

4. In a window screen, in combination with the wire screening, a frame therefor formed from an integral strip of sheet metal, bent into hollow shape with its longitudinal side edges projecting toward the screening, one edge formed into a seat segmental in cross section, and the other edge bent obliquely toward the opposing seat to form a resilient locking member, and having a molding for the vertical sides of the frame bent inwardly to form a groove, with a rod between which and the segmental seat the wire screening is engaged, with the rod locked in position by the resilient member of the molding, and a box having telescopic engagement with the top and bottom portions of the frame, with plates extending at right angles from the box, having telescopic engagement with the groove walls of the side portions of the frame to lock the frame at the corners, and a spring-pressed rod seated in the box and provided with a cover to engage the guide rail to hold the screen in place.

5. In a window screen, the combination with a hollow molding for the sides and top and bottom of the frame, and with grooves formed in the vertical portions, and one of the grooves having its base cut away at the lower end, of a rod mounted in the horizontal portion of the frame, with a cover plate therefor projecting through said cut away portion and a coiled spring on the rod to force the cover plate against the guide rail to hold the screen thereon.

HENRY HIGGIN.
